UNITED STATES PATENT OFFICE.

JOHN LAWSON, OF CENTRAL FALLS, RHODE ISLAND, ASSIGNEE TO HEMPHILL MANUFACTURING COMPANY, A CORPORATION OF RHODE ISLAND.

COMBINED THREAD-BINDER AND THREAD-SEVERING DEVICE FOR KNITTING-MACHINES.

1,293,813.

Specification of Letters Patent. Patented Feb. 11, 1919.

Application filed February 2, 1912. Serial No. 674,893.

To all whom it may concern:

Be it known that I, JOHN LAWSON, a citizen of the United States, residing at Central Falls, in the county of Providence and State 5 of Rhode Island, have invented certain new and useful Improvements in Combined Thread-Binder and Thread-Severing Devices for Knitting-Machines, of which the following is a specification.

10 In a co-pending application for patent (Serial No. 604,550) for improvement in thread-severing device for automatic knitting-machines, filed by me in the U. S. Patent Office, the device forming the subject of that application is combined or associated with thread-binding means for holding the severed ends of the temporarily inactive or "floating" threads; the movements of the thread-binding device being effected 15 and controlled by one or more of the thread-guides or "feeders." As formerly constructed, the additional work involved in thus actuating the binder device through the medium of the thread-guides prevented the 20 latter from moving normally at times; in some instances, too, the resistance or downward pressure of the binder itself upon the thread-guide was sufficient to swing the latch-ring, having the binder device secured 25 thereto, bodily upward a short distance, thereby causing abnormal action.

The object of the present invention is to produce in a knitting-machine combined thread-binding and thread-severing mechanism in which the above named objections 30 or disadvantages are wholly overcome, thereby rendering the device more simple, efficient and reliable. By means of the present invention, the same, when mounted 35 and in normal action, is capable of having positive opening and closing movements imparted to the thread-severing and thread-binding elements; the thread-binder at the same time being further adapted for independent opening and closing movements 40 when the thread-severing members are in the normally closed position.

In the accompanying sheet of drawings, Figure 1 represents an end elevation, in partial section, and viewed from the left of 50 Fig. 2, of portions of an automatic knitting-

machine embodying my present invention, the thread-cutting and thread-binding mechanisms being normally closed; Fig. 2 is a corresponding front side elevation, in 55 partial section; Fig. 3 is a side elevation, in enlarged scale, showing the thread-cutting device in the normally closed position, corresponding with Fig. 1; Fig. 4 is a similar side view showing the cutting jaws in the 60 open position; Fig. 5 is a cross-sectional view, taken on line 5—5 of Fig. 4; and Fig. 6 is an inverted plan view, corresponding with Fig. 4.

In my present improved thread-cutting device proper, the latter and also its actuating mechanism are in some respects similar to the corresponding parts represented in my co-pending application before referred to.

The rotary needle-cylinder N, together with co-operating parts, of a circular knitting-machine are mounted on a table of the frame or housing a. To the rear of the cylinder is positioned a vertical post c¹ having a latch-ring c hinged thereto, substantially as usual. To an arm c² of the latch-ring is secured a bent bracket member b having its opposite or inner end terminating in a normally horizontal notched flat guide-plate b¹. The latter is disposed centrally 70 within the usual needle-row n, shown by dotted lines in Fig. 6, and just above the stitch-ring k of the cylinder; the plate's outer edge b² lies contiguous to the back of 75 the needles—see Fig. 6.

The movable shearing or thread-cutting blade m is pivoted at n¹ to the vertical edge of the said bracket b and arranged to co-operate with the relatively stationary companion shear-plate m¹ secured to the bracket. A thin, flat plate p or auxiliary means for engaging the threads is fixed to the blade m and extends inwardly therefrom so as to bear against the underside of 90 the relatively stationary base-plate b¹ when the movable thread-severing blade m is normally closed—see Fig. 3.

The means represented for actuating the severing device and controlling its movements consist of a revoluble cam-disk i having suitably located, peripherally spaced

lugs i^1 , a tiltingly mounted lever g having its front end engaging the outer rim of disk i and having its rear end jointed to a vertical rod g^1 , in turn jointed to an end of a short, tiltingly mounted lever g^2 , the latter's other end being jointed to the vertically guided connecting-rod or link g^3 ; the upper end of this link is slidably jointed to the slotted rear portion of the main actuating arm or lever h , pivoted at h^1 to the said bracket b , the other or front end of lever h being suitably connected to said cutting-blade m , whereby the angular movements imparted to lever h by the disk i and said intervening members causes the cutter to swing or vibrate on its pivot n^1 , as in opening and closing the thread-severing means.

The actual thread-severing members, m, m^1 , remain in the normally closed position—see Figs. 1 and 3, during the entire knitting of the stocking, except at the several points or places where the device is quickly actuated automatically to sever the threads, as for instance, when a thread is to be made temporarily idle and another thread introduced into knitting action.

It may be stated that the drawings represent portions of a stocking-knitting machine of a type having a cam-shaft s^1 on which are mounted cams, etc., whose angular movements are effected in an intermittent manner through the medium of a pattern-chain and coöperating means (not shown) in a well-known way. The said shaft and its members are arranged to make only one complete revolution during the production of each tubular stocking or tubular unit.

Thus it will be obvious that whenever a lug i^1 of the movable cam disk i engages lever g , the latter is thereby quickly oscillated and causes cutter m to swing from the normally closed position, shown in Fig. 3, to the full open position, shown in Fig. 4. At the instant the said cam-shaft in its movement carries the lug past the lever g , the latter, by means of spring s^2 connected to it, is caused to drop and bear against the disk's rim, the result being to automatically close the swinging cutter, thereby at the same time shearing or severing the thread lying between the cutters and web, and also causing the plate p to hold in position the other end of the thread, the latter extending from the supply bobbin.

In Fig. 2 d^6 indicates a yarn-guide in the dropped position, corresponding to normal knitting, and Fig. 5, shows the guide elevated, as when the thread is inactive. The tiltable lever g is pivoted at a^2 to the main frame, substantially as indicated in Fig. 1. The arrow 2 (Fig. 4) indicates the direction of movement of the link g^3 , etc., to close the cutting-jaws.

The said thread-severing device and its operating mechanism are associated or com-

bined with a main binding device adapted for holding the ends of the temporarily inactive knitting-threads. This binding device consists essentially of a horizontal bent U-shaped rod, indicated in dotted lines in Fig. 6, having one member or arm, d , adjacent the said cutters mounted to swing in bearings disposed on the upper face of the said plate b^1 . The other arm d^1 , when the device is depressed, is adapted to yieldingly bear against the plate's upper surface for binding or holding therebetween the severed end portion of the live thread. To the rear end of arm d is adjustably secured a short swinging crank or lever e , its free end extending transversely of bracket b and disposed horizontally between said members h and m^1 , and below the member h . A spring e^1 connects the members h and e , as clearly shown. In order to maintain a fixed minimum vertical distance between the levers e and h , and also to provide means for actuating the binder simultaneously or in unison with the angular movements of the lever h , a vertical space member f is secured to or integral with the latter, its lower end bearing against the lever e . Thus, it is obvious that a downward movement of the inner or unslotted portion of lever h acts to forcibly separate or open the thread-severing members, opens the auxiliary thread-supporting member p , and at the same time acts to swing upward the main binding member d^1 to release the end of the supply thread. While the devices are thus temporarily open, the immediately preceding thread x last moved out of knitting action, extends from its temporarily elevated thread-guide d^6 to and under the arm d^1 into the open notch b^3 of plate b^1 , and is superimposed on the auxiliary plate p and cutter m . Figs. 4 and 5 represent the corresponding open position and relation of the devices. At substantially the same instant that the plate p swings upward and positions the thread, the cutters sever it, and the binder arm d^1 yieldingly engages the thread, thereby clamping the thread against the face of the plate b^1 . Obviously the binder element may be manually actuated at will by simply overcoming the tension of the said spring e^1 .

The tension of the connecting-spring e^1 , in coöperation with the space member f interposed between the levers e and h , causes the thread-cutting and thread-holding or binding devices to positively close when the inner arm of lever h is moved upward. When the said parts are in the thus normally closed position the spring-pressed thread-binding or clamping element itself is capable of being swung open by hand to release the thread independently of the said actuating mechanism, the connecting spring e^1 rendering the device self-closing, as before stated.

I claim as my invention:

1. In an automatic knitting-machine having a revoluble cylinder provided with needles and sinkers, and coöperable means for knitting a fabric, the combination therewith of a pair of shearing blades for severing the thread, one of said blades being movable relatively to the other, a pivoted operating arm having said movable blade joint-connected therewith, said arm having an arc-shaped slot formed in its outer end portion, a thread-binder or clamping device disposed contiguous to said thread-severing device arranged for holding a plurality of temporarily inactive threads and actuated by said arm, means engageable with said arc-shaped slot for actuating the arm in an intermittent manner, and having said binding device arranged to yieldingly clamp the thread immediately preceding its severance by the shearing device.
2. In an automatic knitting-machine of the general character described, the combination with a revoluble needle-cylinder provided with needles and sinkers, and means coöperating therewith for knitting a web, of movable guides for feeding the knitting threads to the needles, means for severing the thread or threads, means for holding one or more of the temporarily inactive knitting threads in a stationary position, said thread severing and holding devices being positioned contiguous to each other and normally located within the needle row of the cylinder, a swinging arm having an arcuate slot therein, both the thread-severing and thread-clamping or holding devices being operatively connected to said swinging arm, the latter arranged to cause substantially simultaneous opening of the said thread cutting and clamping devices, means connecting said arm with a member of said clamping device whereby the latter in closing is adapted to yieldingly engage the thread thereunder, and means for oscillating said arm, said last-named means including a rod jointed to the slotted end of the arm and capable of movement in its slot.
3. In an automatic knitting-machine of the general character described, having a revoluble knitting cylinder provided with needles and sinkers and the usual accessories for knitting, the combination of a swinging latch-guard having a substantially flat plate member normally positioned within the row of needles and movable with the latch-guard, a revoluble main cam-shaft, thread-severing and thread-clamping devices carried by the latch-guard encircled by the needles, a swinging main lever also carried by the latch-guard and actuated from the cam-shaft for closing and opening said thread-severing and thread-clamping devices, and means yieldingly connecting said main lever and thread-clamping device,

whereby the latter, when normally closed, is capable of being manipulated independently to open the clamp.

4. In a knitting-machine, the combination with a main operating lever pivotally mounted on and carried by an element of a latch-guard, and means for swinging the lever on its pivot, of independently swinging thread-severing and thread-clamping devices actuated and controlled by the movements of said lever, said clamping device arranged, when normally closed, to yieldingly engage the thread, means interposed between the main operating-lever and a member of the clamping device for controlling the angular movement of the latter, and self-closing means connected with the clamping member whereby it may be manually opened at will while the clamping member is in the normally closed position.

5. In an automatic knitting-machine, the combination with a needle-carrying annular cylinder, and a movable latch-guard mounted thereabove, of a horizontally disposed supporting base or plate fixed to and adapted to move bodily with the latch-guard and normally positioned within the needle-row, a thread-severing device secured to said plate, a device having a member thereof mounted for oscillation so as to temporarily position and support the thread so as to be acted upon by the cutters, a thread-binding device mounted on said plate, means for actuating the thread-severing device, means connected with the latter for causing its movements to actuate the thread-binding device, and having the latter further adapted to be opened and closed independently at will while the thread-severing device is normally closed.

6. A knitting machine having in combination a latch-ring, a supporting member secured to said latch-ring, a thread-severing member and a thread-clamping member independently mounted on said supporting member, an operating lever, and connections from said operating lever to both said thread-severing member and said thread-clamping member for actuating the same.

7. A knitting machine having in combination a latch-ring, a supporting member secured to said latch-ring, a thread-severing member and a thread-clamping member independently mounted on said supporting member, an operative lever mounted on said supporting member, and connections from said operating lever to both said thread-severing member and said thread-clamping member for actuating the same.

8. A knitting machine having in combination a latch-ring, a supporting member secured to said latch-ring, a thread-severing member and a thread-clamping member independently mounted on said supporting member, an operating lever mounted on said

supporting member, connections from said operating lever to both said thread-severing member and said thread-clamping member, a cam-shaft and connections from said cam-shaft to said operating lever.

9. A knitting machine having in combination a latch-ring, a supporting member secured to said latch-ring, a thread-severing member and a thread-clamping member mounted on said supporting member, an op-

erating lever adapted to actuate said thread-severing and said thread-clamping members, a cam-shaft, and means carried thereby for operating said lever.

In testimony whereof I have affixed my 15
signature in presence of two witnesses.

JOHN LAWSON.
